CLAIM

The ornamental design for a shank for a threaded fastener bit driver, as shown and described.

DESCRIPTION

FIG. 1 is a perspective view taken from the front and right side of a shank for a threaded fastener bit driver in accordance with our new design;

FIG. 2 is a perspective view taken from the back and left side of the shank for a threaded fastener bit driver of FIG. 1; FIG. 3 is a left side elevation view of the shank for a threaded fastener bit driver of FIGS. 1 and 2, with the right side elevation view being a mirror image of FIG. 3; and, FIG. 4 is a front view of the shank for a threaded fastener bit driver of FIGS. 1-4, with the back view being identical to the front view of FIG. 4.

The broken lines shown are included for the purpose of illustrating portions of the shank for a threaded fastener bit driver that form no part of the claim. The shading lines in the drawings show contour and are not intended to indicate surface orientation.

1 Claim, 2 Drawing Sheets
